UNITED STATES PATENT OFFICE.

WILLIAM J. HAGMAN, OF PHILADELPHIA, PENNSYLVANIA, ASSIGNOR TO
NILES-BEMENT-POND COMPANY, OF JERSEY CITY, NEW JERSEY.

FLANGING-PRESS.

SPECIFICATION forming part of Letters Patent No. 703,406, dated July 1, 1902.

Application filed March 24, 1902. Serial No. 99,647. (No model.)

To all whom it may concern:

Be it known that I, WILLIAM J. HAGMAN, a citizen of the United States, residing at Philadelphia, Philadelphia county, Pennsylvania, have invented certain new and useful Improvements in Flanging-Presses, of which the following is a specification.

This invention pertains to improvements in flanging-presses of that common class for boiler-work and the like in which the work is operated upon by a flanging-tool operated by a pressure-cylinders supported by the head-plate of the press.

The present invention will be readily understood from the following description, taken in connection with the accompanying drawings, in which—

Figure 1 is a front elevation, part vertical section, of the actuating-cylinder for the flanging-press of the class above referred to and embodying my present invention, a portion of the head-plate of the press appearing in vertical section; Fig. 2, a side elevation of the same; Fig. 3, a plan of the cylinder and head-plate, and Fig. 4 a bottom view of that portion of the head-plate at the actuating-cylinder.

In the drawings, 1 indicates the usual head-plate of a flanging-press, designed, as usual, to be supported over the base-plate of the press by means of suitable vertical stretchers or columns; 2, a large opening through the head-plate under the position of the actuating-cylinder; 3, the actuating-cylinder, of usual hydraulic type, vertically disposed over the opening 2 in the head-plate; 4, stretchers by means of which the cylinder is rigidly secured to the head-plate; 5, vertical guideways formed in opposite side walls of opening 2 in the head-plate; 6, the ram of the cylinder; 7, a cross-head at the lower end of the ram and extending from one to the other of the guideways 5 in the opening of the head-plate, this cross-head having a flat lower surface; 8, guide-lugs upon the cross-head engaging with the guideways 5 in the head-plate, this guiding arrangement preventing angular motion of the cross-head and ram and steadyng the free end of the ram in its reciprocations; 9, a pair of drawback-cylinders disposed vertical one at each side of the main cylinder;

10, the piston-rods of the drawback-cylinders, the same extending downwardly from their cylinders and being attached to the cross-head 7 at opposite sides of the ram; 11, a pair of T-slots disposed parallel with each other in the lower face of cross-head 7; 12, the flanging-tool or its holder; 13, a flange on the upper end of the flanging-tool, seating against the lower face of the cross-head, and 14 bolts engaging this flange and the slots 11 of the cross-head and serving to fix the flanging-tool to the cross-head and permit of the flanging-tool being shifted to various positions relative to the axis of the ram.

For specially heavy work or for work permitting of such position the flanging-tool is adjusted upon the cross-head so as to occupy a position in vertical line with the ram, and the machine is then employed as usual. Where the conditions of the work require a change in the position of the flanging-tool relative to the other parts of the press, then the flanging-tool is shifted upon the cross-head and resecured in a position eccentric to the ram. In the exemplification the opening 2 in the head-plate is shown as rectangular, the cross-head of corresponding shape, and a single pair of slots 11 is shown; but this particular form for the opening and cross-head is not essential, nor is it essential that the shifting motion of the flanging-tool upon the cross-head be limited by a single pair of slots or to a single line of adjusting motion.

I claim as my invention—

1. In a flanging-press, the combination, substantially as set forth, of a head-plate provided with an opening through it, an actuating-cylinder fixedly secured over said opening, a ram projecting from the cylinder into the opening, a cross-head disposed at the lower end of the ram and reciprocating within said opening, and a flanging-tool secured within said opening to the lower face of the cross-head and arranged for horizontal adjustment thereon.

2. In a flanging-press, the combination, substantially as set forth, of a head-plate provided with an opening through it having guideways supported by its walls, an actuating-cylinder fixedly secured over said opening, a ram projecting from the cylinder into

the opening, a cross-head at the lower end of the ram and engaging said guideways in the opening of the head-plate, and a flanging-tool secured within said opening to the lower face of the cross-head and arranged for horizontal adjustment thereon.

3. In a flanging-press, the combination, substantially as set forth, of a fixedly-supported actuating-cylinder, a ram projecting axially therefrom, a cross-head at the end of

the ram provided with a pair of parallel T-slots in its face, a flanging-tool provided with a flange at its end to seat against the cross-head, and bolts engaging said flange and T-slots.

WILLIAM J. HAGMAN.
